UNITED STATES PATENT OFFICE.

ROBERT McCLENATHEN, OF AKRON, OHIO, ASSIGNOR, BY MESNE ASSIGNMENTS, TO
INTERNATIONAL HARVESTER CORPORATION, A CORPORATION OF NEW JERSEY.

IGNITION SYSTEM.

1,221,199.

Specification of Letters Patent. Patented Apr. 3, 1917.

Application filed February 13, 1913. Serial No. 748,132.

To all whom it may concern:

Be it known that I, ROBERT McCLENATHEN, a citizen of the United States, residing at Akron, in the county of Summit and State of Ohio, have invented certain new and useful Improvements in Ignition Systems, of which the following is a full, clear, and exact specification.

This invention relates to ignition systems. In all ignition systems in which only the magneto is used, the operation of the engine is dependent upon the uninterrupted performance of the magneto. If, for any reason, the magneto fails to properly operate, the engine stops and cannot be run again until the magneto is repaired. Again in ignition systems in which only batteries are used in connection with a coil, the engine would be rendered inoperative by a break down in any part of the system. In any system in which batteries are used in connection with a magneto, a break down of the magneto puts the engine out of use, and prevents the auto vehicle, in which the engine may be installed, from giving service for a considerable period of time, depending upon the locality in which the break down occurs, and whether or not repairs can readily be made. In other words, the auto vehicle may be miles from a place where a new magneto may be obtained or repairs made on the broken one. It is therefore seen that in any ignition system where even both magneto and battery are used, breakdowns occur in one part of the system which reduces the service of the engine or vehicle, for a given period of time, to a much lower percentage than would otherwise be the case if the ignition system was able in itself to take care of the emergency without any delay. Many engines are equipped with two independent ignition systems so that in case one of the ignition systems fails the other can be used, but such combination of ignition systems is not only cumbersome, complicated, and expensive, but requires more care

and attention to keep both ignition systems in operating condition.

It is, therefore, the object of my invention to overcome the above mentioned difficulties in connection with ignition systems, and to prevent an engine being rendered inoperative due to any failure in the ignition system, and at the same time to provide a compact, simple and efficient ignition system at a minimum cost.

This object is accomplished by providing an ignition system in which there are a plurality of different ways of producing the necessary spark without duplicating the parts or making one way dependent upon the use of parts required to produce the spark in one of the other ways.

In this system, which includes a magneto, battery, and timers, one of which is removable with and forms a part of the magneto, all of which are adapted to coöperate with one coil in common, the magneto can be removed from the ignition system and the necessary spark, either single or vibrating, can be produced by means of the battery, a timer, and coil; or one of the timers can be removed and the spark produced by means of the battery current operating through the magneto timer and the coil; or with the battery and one timer removed, the spark produced by the magneto a timer and coil alone.

This invention is illustrated on the accompanying sheets of drawings in which Figure 1 is a diagrammatic plan of the ignition system;

Fig. 2 is a wiring diagram of my ignition system including a controlling switch;

Fig. 3 is a diagram of connections showing an arrangement in which the necessary spark or sparks are produced by the battery current passing through a timer and coil;

Fig. 4 is a diagram of connections showing an arrangement in which the spark is produced by the battery current passing through a portion of the magneto and coil;

Fig. 5 is a diagram of connections showing an arrangement in which the spark is produced directly by current generated in the magneto which passes through the same coil;

Fig. 6 is an end view of a timer;

Fig. 7 is an end view of the breaker box which forms part of the magneto; and,

Fig. 8 is a diagram of connections similar to the one shown in Fig. 2, but being particularly designed to be used where more than two cylinders are employed.

The various novel features of my invention will be apparent from the description and drawings, and will be particularly set forth in the appended claims.

Like parts will be designated by the same reference characters in all figures of the drawings.

My ignition system includes a battery or set of batteries 10, for sake of illustration, two series of five each being connected in parallel as shown. In Fig. 1 directly to the right of the set of batteries 10, the same set is shown connected in series, the batteries being changed over to the series arrangement when such batteries or cells are in a comparatively weak condition. A connection 11 from one terminal of the battery taken as a whole, is grounded, as indicated at 12, the other terminal of the battery 10 being connected by a wire 13 to one coil box terminal 14 connected to one end of a primary or low potential coil 15 (see Figs. 2 to 5, inclusive), the other end of the said primary low potential coil 15 terminating at terminal 15^a of the coil box 16, from which a wire 17 leads to one terminal 18 of a timer 19 which, is grounded every revolution of the engine by engaging a timer terminal 20 (see Fig. 6) connected by a wire 21 to the ground terminal 22 of the coil box 16 which in turn is connected by a wire 23 to a ground terminal 24 secured to the frame of a magneto 25. This completes a circuit from the grounded battery 10 through the low potential or primary coil 15, timer 19 and through the ground or metallic frame of the engine or vehicle back to the battery. By now referring more particularly to Fig. 3 of the drawings, it will be seen that a vibrator or interrupter 26 is connected in circuit between the battery 10 and the low voltage primary coil 15. The movable member 27 of the vibrator 26 is provided with an armature which is adapted to be attracted by a soft iron core 28, located within the coil 15, when said core becomes magnetized. A condenser 29 is connected across platinum contact points 30 of the vibrator 26 to prevent burning or destruction of said contact points. Superimposed upon the primary low voltage coil 15 is a secondary or high voltage coil 31, the ends of which are con-

nected to electrodes or spark plugs 32, which are to be properly located for ignition purposes. Another condenser 33 is connected across the timer 19 to prevent burning of the contact points thereof. When the circuit is completed through the contacts 18 and 20 of the timer upon each revolution of the engine, current from the battery passes through the primary low potential coil 15, causing the core 28 to be magnetized, thus actuating the movable member 27 of the vibrator, making and breaking the circuit at the contact points 30. This repeated interruption at the vibrator contact points of the current through the primary coil 15 induces a series of high voltage impulses through the secondary coil 31 causing a shower of sparks at the spark plugs.

Thus far the ignition system has been considered from the stand point of producing a spark by current from the battery 10, through the vibrator 26, coil 15, and timer 19. The spark is usually produced in this way for starting purposes.

The ignition system will now be considered from the stand point of the battery current passing through the low potential coil 15 and circuit breaker 34 of the magneto 25. This circuit breaker 34, which really is a part of the magneto structure forms a second timing device. In this connection particular attention is directed to Figs. 1-2-4-7. It will be particularly noted by referring to the connection in Fig. 4 that the vibrator 26 is dispensed with and the circuit breaker or timer 34 of the magneto is substituted for the timer 19 shown particularly in Fig. 3. Current from the battery 10, with the connections shown in Fig. 4, passes through conductor 13 to the coil box terminal 14, through the low potential primary coil 15, coming out of the coil box at terminal 35, through conductor 36 to one terminal 37 of the circuit breaker 34, through the contacts of circuit breaker 34, through a spring 38, indicated by a dotted line, to the ground terminal 24 on the magneto frame, back to the other terminal of the battery 10. The movable contact 39 of the circuit breaker 34 is mounted on one end of a lever 40, at the other end of which is a disk 41, which is held in engagement with a rotatable cam 42 mounted on the shaft of the magneto 25, said disk 41 being held against said cam by said spring 38, which tends to hold the contacts of the circuit breaker 34 in engagement with each other.

During the time that the disk 41 is held in engagement with the round portion of the cam 42, the contact points of the circuit breaker 34 are held out of engagement with each other, but when the flat portion 43 of the cam comes adjacent to said disk 41 said

disk is pressed against said flat portion by the action of spring 38, causing the contact tips of the circuit breaker 34 to engage with each other, thereby completing a circuit permitting current to pass through the low potential coil 15, thus energizing the soft iron core 28. As soon as the disk reaches the round portion of the cam 42 the contacts of the circuit breaker 34 are separated and the current flowing through the primary coil 15 is interrupted. This interruption of the primary current induces a high voltage current in the secondary circuit 31 which produces the necessary spark at the spark plugs.

15 A condenser 44 similar to condenser 33 is connected across the contacts of the circuit breaker 34 to prevent the burning of said contacts. In this arrangement of connections in my ignition system, it is seen that

20 the necessary spark is produced by a current from the battery 10 passing through the same primary coil 15 that was used in the system of connections particularly shown in Fig. 3 and that said current passes

25 through the contacts of the circuit breaker 34 of the magneto 25 instead of the timer 19, as shown in Fig. 3. It is therefore apparent that if, for any reason, the timer 19 should get out of order the spark could still

30 be produced, the circuit being interrupted at the circuit breaker 34.

In the two systems of connections thus far considered, the battery has been employed as the source to supply the necessary current, and in one case the timer and vibrator were used, (see Fig. 3) and in the second case the circuit breaker or timer of the magneto was used, (see Fig. 4). In still a third arrangement of connections, capable of being made in my ignition system, current is generated in the magneto and passes through the same primary coil 15 that is used in the other connections, the circuit being broken at the circuit breaker or timer 34 of the magneto. In this last mentioned arrangement the battery 10, timer 19 and vibrator 26 are not necessary and are not employed.

Referring now particularly to Figs. 1-2-5-7, the rotating member 45 of the magneto is provided with a coil 46 in which current is generated, one end of said coil being grounded as indicated at 47 and the other end of which is connected through four suitable spring-pressed current-conducting members 48 which are held against a conducting plate 49, from which the current passes through a magneto terminal 50, through coil box terminal 51, low voltage primary coil 15, coil box terminal 35, conductor 53, magneto terminal 37, through the platinum contact tips of circuit breaker or timer 34, to the ground terminal 24 on the frame of the magneto, thus completing the circuit. This circuit is interrupted at the

circuit breaker 34, producing in like manner the necessary spark at the spark plugs. In this case, however, the current is generated in the magneto itself, this system of connections not including the battery 10, vibrator 26 or timer 19.

It is to be noted in particular that in each one of the systems of connection disclosed in Figs. 3-4-5 the same primary low voltage coil 15 is common to all connections. If the magneto should be out of order, the same could be removed and the necessary spark would still be produced by the battery current passing through coil 15 and timer 19; or if the battery was out of order the same could be discarded and the spark produced by current generated in the magneto, the current passing through the circuit breaker 34; and if the timer 19 got out of working order the current from either the battery or the magneto could be used in producing the necessary spark, the circuit of the current being made and broken by the circuit breaker 34 of the magneto.

Thus far no reference has been made to the master or unitary control switch which controls the connections disclosed in Figs. 3-4-5. It is obvious that various types of switches can be used for this purpose. For the sake of illustration, I have shown a suitable switch 54, the key or handle 55 of which is shown and indicates the positions of said switch in Figs. 3-4-5. This switch 54 is provided with three movable contacts 56, 57, and 58, which are operatively connected in any suitable manner with the key or operating handle 55. As shown in Fig. 2, the switch is in off position and no spark is being produced at the spark plugs. In this off position of the switch the movable contact 56 engages a stationary contact 59, and the movable contact 57 engages a stationary contact 63. No circuit, however, is completed by the engagement of said contacts.

Let it be assumed that it is desired to start an internal combustion engine. It will therefore be necessary to produce the necessary spark to ignite the explosive mixture in the combustion chamber of said engine. To produce this spark for starting purposes the switch is turned in a counter clock wise direction until the movable contact segment 57 engages stationary contact 64, the movable contact 57 still remaining in engagement with stationary contact 63. At the same time the movable contact 56 is moved into engagement with stationary contact 60, bridging stationary contacts 59 and 60 and movable contact 58 is moved into engagement with stationary contact 62. With the switch in this position connections, which are illustrated in Fig. 3, are made. Following said connections in Fig. 2 it will be seen that current passes from battery 10, through

conductor 13, coil box terminal 14, stationary contact 63, movable contact 57, stationary contact 64, primary low voltage coil 15, stationary contact 60, movable contact 56, stationary contact 59, vibrator 26, coil box terminal 15^a, timer 19, to ground and to the other side of the battery 10, the necessary spark being produced as herein above considered with respect to connections shown in Fig. 3. In the diagram shown in Fig. 2 and in this particular switch position, it is to be noted that there is another connection from stationary contact 60, through a button contact switch 66, movable contact 58, stationary contact 62, coil box terminal 22 to ground. By closing the push button switch 66 a circuit will be completed independent of the timer 19 for producing a spark for starting purposes without cranking the engine. The condenser 29 in Fig. 2 may be used for protecting both the vibrator and the timer 19. If it is desired however, two separate and independent condensers may be used for said purposes.

If for any reason the timer 19 or vibrator should get out of order or if for any reason it is desired to pass the current through the circuit breaker or timer 34 of the magneto instead of the timer 19, the switch may be moved further in a counter-clockwise direction until the movable contact 56 passes out of engagement with the stationary contact 59 and into engagement with contact 61, thus bridging contacts 60 and 61, stationary contacts 63 and 64 being still bridged by movable contacts 57, and the circuit will be completed from one side of the battery 10 through conductor 13, coil box terminal 14, contacts 63, 57, and 64, primary low voltage coil 15, contacts 60, 56, and 61, coil box terminal 35, conductor 36, circuit breaker or timer 34 of the magneto to the ground and to the other side of the battery, the necessary spark being produced as already considered in connection with the diagram shown in Fig. 4, which corresponds to this position of the switch.

If the battery, timer 19, or vibrator have gotten out of order or for any other reason it is desirable to produce the spark by current generated in the magneto, the circuit being made and broken through the circuit breaker 34 of the magneto independent of the battery, vibrator, or timer, the switch 55 may be turned still further in a counter-clockwise direction until the movable contact 57 has passed out of engagement with the stationary contact 63 and into engagement with stationary contact 65, thereupon 60 bridging stationary contacts 64 and 65, stationary contacts 60 and 61 still being bridged by movable contact 56, the circuit being completed for the passage of current generated in the magneto from grounded coil 46 thereof, through coil box terminal 51, contacts 65 65, 57, and 64, primary coil 15 contacts 60, 56, and 61, coil box terminal 35, conductor 36, and circuit breaker or timer 34 of the magneto to ground. The necessary spark is thus produced as already considered in connection with the diagram shown in Fig. 5 which corresponds to the position of the switch just hereinabove considered. The magneto 25 can be driven from any suitable source through the proper gears located in the box 69 and a coupling 70. Instead of calling the primary and secondary spark-producing windings 15 and 31 coils, they might properly be called a transforming or translating device.

From the above it will be seen that the spark can be produced by a current from the battery passing through the vibrator 26, coil 15, and timer 19; that a spark can be produced by a current from the battery through the same coil 15 and through circuit breaker or timer 34 of the magneto; and that the spark can be produced by a current generated in the magneto and passing through the same coil 15, and circuit breaker or timer 34 of the magneto, the circuits all being controlled by a master switch thereby providing a unitary selective ignition system. Three independent ways are therefore provided in my ignition system for producing the spark. This ignition system is therefore properly called the "triple ignition system." As above considered, if the battery goes wrong the spark can be produced by current generated in the magneto; if the timer gets out of running order, the current can be directed through the circuit breaker of the magneto, whether or not the current is generated in the battery or in the armature coil of the magneto; and if the magneto is disabled in any way the spark may be produced through the timer. At the same time only the single translating device with its primary and secondary coils is used in this ignition system regardless of the other circuit connections.

The circuits arrangements thus far considered are particularly adapted for use in connection with an internal combustion engine having two cylinders. This "triple ignition system" however can be equally well employed where more than two engine cylinders are used in which an explosive mixture is ignited. For the sake of illustration, I will show the same ignition system as used in connection with four cylinders. Particular attention is directed to Fig. 8, which discloses practically the same circuit connections and wiring layout as shown in Fig. 2 with the exception that in Fig. 8 a distributor 70^a, having four stationary contacts 71, 72, 73, and 74 and one movable contact 75 are shown, the same being shown diagrammatically as such distributors in themselves are old. The movable contact 130

75 is connected to one end of the secondary or high voltage coil 31, the other end of said coil being connected to ground. With a distributor used in connection with four cylinders, it is necessary that the movable contact 75 thereof be rotated at half engine speed so that the circuit from the secondary coil will be connected with the proper cylinder at the right time. In view 10 of the fact that the magneto as here shown runs at engine speed it will be necessary where four cylinders are used to provide the cam 42 with two flat spots similar to the one 43, said flat spots being diametrically opposite to each other for the purpose of causing the circuit at the circuit breaker or timer 34 of the magneto to be interrupted twice each revolution of the magneto and engine 15 to produce the proper number of sparks at the right time. Where the timer 19 is used instead of magneto timer 34 and said timer runs at engine speed, two stationary contacts similar to the contact 18 are necessary in the same manner as considered in connection 20 with the magneto timer. If the timer 19 runs at half engine speed four stationary contacts will be necessary. Or, instead of using four stationary contacts, a reciprocating contact member could be used operated 25 by a four point cam, closing the circuit four times during each revolution of the timer. Of course the distributor, as considered in my system where only one is used is operated independently of the magneto 30 and timer and a removal of the magneto and a timer would not affect its operation. Where however two distributors are used one of them may be connected and operated with either the magneto or a timer. In the 35 case where two distributors are used and it is desired to remove the magneto for repairs the distributor connected therewith being removed at the same time, the engine can still be operated through the agency of the 40 other distributor which is left intact.

It is evident that there may be various other modifications and arrangements of my ignition system other than those which I have herein particularly described and 45 shown, and it is my intention to cover all such modifications and arrangements which do not involve a departure from the spirit and scope of my invention as set forth in the appended claims.

50 55 What I claim as new is—

1. In an ignition system, the combination of a source of current supply, a coil adapted to receive current therefrom, a plurality of selective timing devices through one of which current always passes when supplied to said coil under normal running conditions, and unitary means including a single switch for controlling the effectiveness of said timing devices.
- 60 65 2. In an ignition system, the combina-

tion of a source of power supply, a translating device adapted to receive power therefrom, selective timing device means through one of which power always passes when supplied to said translating device under 70 normal running conditions, and a single switch for controlling the effectiveness of said timing device means.

3. In an ignition system, the combination of a source of current supply, a translating device adapted to receive current therefrom, a plurality of timing devices by means of which current supply to said translating device may be affected, and a vibrator by means of which the circuit of the translating device may be made and broken as current passes through one of said timing devices.

4. In an ignition system, the combination of a source of current supply, a translating device adapted to receive current therefrom, a plurality of timing members by means of which current supply to said translating device may be affected, a vibrator by means of which the circuit of the translating device 80 may be made and broken as current passes through one of said timing members, and means for controlling the effectiveness of said timing members.

5. In an ignition system, the combination 95 of three selective circuits which a current may traverse for producing a spark, a plurality of timing members in said circuits, and means for controlling said circuits whereby one timing member always may be 100 used in the active circuit during normal operating conditions.

6. In an ignition system, the combination 105 of a translating device adapted to produce a spark, a plurality of sources including a magneto for supplying current to said translating device, a plurality of timing members, one being a part of the magneto unit and another mechanically independent thereof, and single means for controlling 110 the supply of said current from either of said sources through different ones of said timing members under different circuit connections.

7. In an ignition system, the combination 115 of a translating device adapted to produce a spark, a plurality of sources including a magneto for supplying current to said translating device, a plurality of timing members, one being a part of the magneto unit and another independent thereof, and single 120 means for controlling the supply of said current from either of said sources through different ones of said timing members, said timing members being independent of each 125 other and only one of said timing members being used at a time.

8. In an ignition system, the combination of a translating device adapted to produce a spark, a plurality of sources including a 130

magneto for supplying current to said translating device, a plurality of timing members, one being a part of the magneto unit, and unitary means for controlling the supply of current from either of said sources through different ones of said timing members.

In testimony whereof I affix my signature, in the presence of two witnesses.

ROBERT McCLENATHEN.
